PC(57) **ABSTRACT**

A common-mode choke coil includes a multilayer body, a first coil, a second coil, a first terminal electrode, a second terminal electrode, a third terminal electrode, and a fourth terminal electrode. The multilayer body includes plural non-conductor layers. The first and second coils are incorporated in the multilayer body. The first and second terminal electrodes are connected to the first coil. The third and fourth terminal electrodes are connected to the second coil. The first coil has a path length L1, the second coil has a path length L2, and the sum of the path length L1 and the path length L2 is less than or equal to 3.4 mm. The respective lower-face electrode portions of the terminal electrodes each have an area of less than or equal to 0.034 μm^2 .

COMMON-MODE CHOKE COIL

CROSS-REFERENCE TO RELATED APPLICATION

This application claims benefit of priority to Japanese Patent Application No. 2020-132929, filed Aug. 5, 2020, the entire content of which is incorporated herein by reference.

BACKGROUND

Technical Field

The present disclosure relates to a common-mode choke coil. More specifically, the present disclosure relates to a multilayer common-mode choke coil including a multilayer body with plural stacked non-conductor layers, and a first coil and a second coil that are incorporated in the multilayer body.

Background Art

A technique that is of interest for the present disclosure is described in, for example, Japanese Unexamined Patent Application Publication No. 2006-313946. The technique described in Japanese Unexamined Patent Application Publication No. 2006-313946 relates to a multilayer common-mode choke coil. The common-mode choke coil is an ultra-small thin-film common-mode choke coil, and capable of high-speed transmission of transmission signals at frequencies near the GHz range. More specifically, Japanese Unexamined Patent Application Publication No. 2006-313946 describes a common-mode choke coil with a cutoff frequency of greater than or equal to 2.4 GHz, the cutoff frequency being defined as the frequency at which the attenuation of a transmission signal (differential-mode signal) reaches -3 dB.

Advances in high-speed communication technology have led to the growing need for a multilayer common-mode choke coil that can, at increasingly higher frequencies, transmit differential-mode signals and suppress common-mode noise components.

SUMMARY

Accordingly, the present disclosure provides a multilayer common-mode choke coil that can, at higher frequencies such as 25 GHz to 30 GHz, and even at very high frequencies such as above 30 GHz, transmit differential-mode signals, and suppress common-mode noise components.

A common-mode choke coil according to preferred embodiments of the present disclosure includes a multilayer body, a first coil, a second coil, a first terminal electrode, a second terminal electrode, a third terminal electrode, and a fourth terminal electrode. The multilayer body includes a plurality of non-conductor layers, the plurality of non-conductor layers being stacked and each made of a non-conductor. The first coil and the second coil are incorporated in the multilayer body. The first terminal electrode and the second terminal electrode are provided on an outer surface of the multilayer body, the first terminal electrode being electrically connected to a first end, the second terminal electrode being electrically connected to a second end, the first end and the second end being different ends of the first coil. The third terminal electrode and the fourth terminal electrode are provided on an outer surface of the multilayer body, the third terminal electrode being electrically con-

2

nected to a third end, the fourth terminal electrode being electrically connected to a fourth end, the third end and the fourth end being different ends of the second coil.

The multilayer body is a cuboid in shape. The cuboid has an upper face, a lower face, a first lateral face, a second lateral face, a first end face, and a second end face. The upper face and the lower face extend in a direction in which the plurality of non-conductor layers extend, and are opposite to each other. The first lateral face and the second lateral face couple the upper face and the lower face to each other, and are opposite to each other. The first end face and the second end face couple the upper face and the lower face to each other, and couple the first lateral face and the second lateral face to each other. The first end face and the second end face are opposite to each other. The lower face is a mounting face that is directed toward a mounting substrate.

The first terminal electrode has a first lateral-face electrode portion provided on the first lateral face, and a first lower-face electrode portion contiguous to the first lateral-face electrode portion and provided on a portion of the lower face.

The second terminal electrode has a second lateral-face electrode portion provided on the second lateral face, and a second lower-face electrode portion contiguous to the second lateral-face electrode portion and provided on a portion of the lower face.

The third terminal electrode has a third lateral-face electrode portion provided on the first lateral face, and a third lower-face electrode portion contiguous to the third lateral-face electrode portion and provided on a portion of the lower face.

The fourth terminal electrode has a fourth lateral-face electrode portion provided on the second lateral face, and a fourth lower-face electrode portion contiguous to the fourth lateral-face electrode portion and provided on a portion of the lower face.

The plurality of non-conductor layers include a first plurality of non-conductor layers and a second plurality of non-conductor layers. The first coil includes a first coil conductor disposed along a first interface, the first interface being an interface between the first plurality of non-conductor layers. The second coil includes a second coil conductor disposed along a second interface, the second interface being an interface between the second plurality of non-conductor layers and different from the first interface along which the first coil conductor is disposed.

To address the above-mentioned technical problem, according to preferred embodiments of the present disclosure, the common-mode choke coil configured as described above has a first characteristic feature and a second characteristic feature. According to the first characteristic feature, the first coil has a path length L1, the second coil has a path length L2, and the sum of the path lengths L1 and L2 is less than or equal to 3.4 mm. According to the second characteristic feature, the first lower-face electrode portion, the second lower-face electrode portion, the third lower-face electrode portion, and the fourth lower-face electrode portion each have an area of less than or equal to 0.034 μm^2 .

According to preferred embodiments of the present disclosure, the stray capacitance between the first coil and the second coil, as well as the stray capacitance between each terminal electrode and the first coil and the stray capacitance between each terminal electrode and the second coil can be reduced. This helps to improve the high-frequency characteristics of the common-mode choke coil.

Other features, elements, characteristics and advantages of the present disclosure will become more apparent from

the following detailed description of preferred embodiments of the present disclosure with reference to the attached drawings.

BRIEF DESCRIPTION OF THE DRAWINGS

FIG. 1 is a perspective view of a common-mode choke coil according to an embodiment of the present disclosure, illustrating the outward appearance of the common-mode choke coil;

FIG. 2 is an exploded plan view of the major components of the common-mode choke coil illustrated in FIG. 1;

FIG. 3 is a plan view of the common-mode choke coil illustrated in FIG. 1, representing a schematic see-through illustration of first and second coils incorporated in a multilayer body as viewed in the stacking direction;

FIG. 4 is a plan view of a first coil conductor included in the first coil of the common-mode choke coil illustrated in FIG. 1, explaining the number of turns of the first coil conductor;

FIG. 5 illustrates the transmission characteristic for common-mode components (Scc21 transmission characteristic) obtained for a common-mode choke coil corresponding to Sample 8, which is one representative example of common-mode choke coil samples fabricated in an exemplary experiment conducted to verify the effects of the present disclosure; and

FIG. 6 illustrates the transmission characteristic for differential-mode components (Sdd21 transmission characteristic) obtained for the common-mode choke coil corresponding to Sample 8.

DETAILED DESCRIPTION

With reference to FIGS. 1 through 4, a common-mode choke coil 1 according to an embodiment of the present disclosure is described below.

As illustrated in FIG. 1, the common-mode choke coil 1 includes a multilayer body 2 having plural stacked non-conductor layers. FIG. 2 depicts representative non-conductor layers 3a, 3b, 3c, 3d, and 3e among these non-conductor layers. In the following description, unless individual non-conductor layers are to be distinguished from each other such as in the case of the non-conductor layers 3a, 3b, 3c, 3d, and 3e illustrated in FIG. 2, reference sign "3" is used for non-conductor layers to generically describe each non-conductor layer. Each non-conductor layer 3 is made of a non-conductor, examples of which include glass and ceramic materials.

The multilayer body 2 is substantially a cuboid in shape that has an upper face 5, a lower face 6, a first lateral face 7, a second lateral face 8, a first end face 9, and a second end face 10. The upper face 5 and the lower face 6 extend in a direction in which the non-conductor layers 3 extend, and are opposite to each other. The first lateral face 7 and the second lateral face 8 couple the upper face 5 and the lower face 6 to each other, and are opposite to each other. The first end face 9 and the second end face 10 couple the upper face 5 and the lower face 6 to each other, and couple the first lateral face 7 and the second lateral face 8 to each other. The first end face 9 and the second end face 10 are opposite to each other. The cuboid may be, for example, rounded or chamfered in its edge and corner portions. The lower face 6 serves as a mounting face that is directed toward a mounting substrate when the common-mode choke coil 1 is mounted to the mounting substrate.

As illustrated in FIGS. 2 and 3, the common-mode choke coil 1 includes a first coil 11 and a second coil 12 that are incorporated in the multilayer body 2. As illustrated in FIG. 1, the common-mode choke coil 1 also includes the following terminal electrodes provided on the outer surface of the multilayer body 2: a first terminal electrode 13, a second terminal electrode 14, a third terminal electrode 15, and a fourth terminal electrode 16.

The first terminal electrode 13 has a first lateral-face electrode portion 13a provided on the first lateral face 7, a first lower-face electrode portion 13b contiguous to the first lateral-face electrode portion 13a and provided on a portion of the lower face 6, and a first upper-face electrode portion 13c contiguous to the first lateral-face electrode portion 13a and provided on a portion of the upper face 5.

The second terminal electrode 14 has a second lateral-face electrode portion 14a provided on the second lateral face 8, a second lower-face electrode portion 14b contiguous to the second lateral-face electrode portion 14a and provided on a portion of the lower face 6, and a second upper-face electrode portion 14c contiguous to the second lateral-face electrode portion 14a and provided on a portion of the upper face 5.

The third terminal electrode 15 has a third lateral-face electrode portion 15a provided on the first lateral face 7, a third lower-face electrode portion 15b contiguous to the third lateral-face electrode portion 15a and provided on a portion of the lower face 6, and a third upper-face electrode portion 15c contiguous to the third lateral-face electrode portion 15a and provided on a portion of the upper face 5.

The fourth terminal electrode 16 includes a fourth lateral-face electrode portion 16a provided on the second lateral face 8, a fourth lower-face electrode portion 16b contiguous to the fourth lateral-face electrode portion 16a and provided on a portion of the lower face 6, and a fourth upper-face electrode portion 16c contiguous to the fourth lateral-face electrode portion 16a and provided on a portion of the upper face 5.

As illustrated in FIG. 2, the first terminal electrode 13 and the second terminal electrode 14 are respectively electrically connected to a first end 11a and a second end 11b, which are different ends of the first coil 11. The third terminal electrode 15 and the fourth terminal electrode 16 are respectively electrically connected to a third end 12a and a fourth end 12b, which are different ends of the second coil 12.

The following description assumes that the non-conductor layers 3a, 3b, 3c, 3d, and 3e are stacked from the bottom to the top in the order depicted in FIG. 2.

Referring to FIG. 2, the first coil 11 has a first coil conductor 17 disposed along the interface between the non-conductor layers 3b and 3c. The first coil 11 has a first extended conductor 19, and a second extended conductor 20. The first extended conductor 19 provides the first coil 11 with the first end 11a. The second extended conductor 20 provides the first coil 11 with the second end 11b. The first extended conductor 19 includes a first connection end portion 23. The first connection end portion 23 is connected to the first terminal electrode 13 at a location on the outer surface of the multilayer body 2. The second extended conductor 20 includes a second connection end portion 24. The second connection end portion 24 is connected to the second terminal electrode 14 at a location on the outer surface of the multilayer body 2.

The first connection end portion 23 is disposed along the interface between the non-conductor layers 3a and 3b different from the interface between the non-conductor layers 3b and 3c along which the first coil conductor 17 is disposed.

The first extended conductor 19 includes a first via-conductor 27, and a first coupling part 29. The first via-conductor 27 is connected to the first coil conductor 17, and penetrates the non-conductor layer 3b, which is located between the first coil conductor 17 and the first connection end portion 23, in the thickness direction of the non-conductor layer 3b. The first coupling part 29 is disposed along the interface between the non-conductor layers 3a and 3b along which the first connection end portion 23 is disposed. The first coupling part 29 connects the first via-conductor 27 and the first connection end portion 23 to each other. The first coupling part 29 is preferably shaped to extend substantially linearly. As a result, an inductance due to the first coupling part 29 can be reduced, and high-frequency characteristics can be thus improved.

As described below, the second coil 12 also has elements similar to those of the first coil 11.

The second coil 12 includes a second coil conductor 18 disposed along the interface between the non-conductor layers 3c and 3d. The second coil 12 includes a third extended conductor 21, and a fourth extended conductor 22. The third extended conductor 21 provides the second coil 12 with the third end 12a. The fourth extended conductor 22 provides the second coil 12 with the fourth end 12b. The third extended conductor 21 includes a third connection end portion 25. The third connection end portion 25 is connected to the third terminal electrode 15 at a location on the outer surface of the multilayer body 2. The fourth extended conductor 22 includes a fourth connection end portion 26. The fourth connection end portion 26 is connected to the fourth terminal electrode 16 at a location on the outer surface of the multilayer body 2.

The third connection end portion 25 is disposed along the interface between the non-conductor layers 3d and 3e different from the interface between the non-conductor layers 3c and 3d along which the second coil conductor 18 is disposed. The third extended conductor 21 includes a second via-conductor 28, and a second coupling part 30. The second via-conductor 28 is connected to the second coil conductor 18, and penetrates the non-conductor layer 3d, which is located between the second coil conductor 18 and the third connection end portion 25, in the thickness direction of the non-conductor layer 3d. The second coupling part 30 is disposed along the interface between the non-conductor layers 3d and 3e along which the third connection end portion 25 is disposed. The second coupling part 30 connects the second via-conductor 28 and the third connection end portion 25 to each other. As with the first coupling part 29 mentioned above, the second coupling part 30 is preferably shaped to extend substantially linearly. As a result, an inductance due to the second coupling part 30 can be reduced, and high-frequency characteristics can be thus improved.

The common-mode choke coil 1 is mounted with the lower face 6 of the multilayer body 2 directed toward the mounting substrate. In one exemplary embodiment of the common-mode choke coil 1, the multilayer body 2 has a length dimension L of greater than or equal to about 0.55 mm and less than or equal to about 0.75 mm (i.e., from about 0.55 mm to about 0.75 mm), which is defined between the first and second end faces 9 and 10 that are opposite to each other, a width dimension W of greater than or equal to about 0.40 mm and less than or equal to about 0.60 mm (i.e., from about 0.40 mm to about 0.60 mm), which is defined between the first and second lateral faces 7 and 8 that are opposite to each other, and a height dimension H of greater than or equal to about 0.20 mm and less than or equal to about 0.40 mm

(i.e., from about 0.20 mm to about 0.40 mm), which is defined between the upper and lower faces 5 and 6 that are opposite to each other.

As is apparent from FIGS. 2 and 3, the first and second coil conductors 17 and 18 of the common-mode choke coil 1 each preferably have a number of turns of less than or equal to about 1.

The number of turns mentioned above is defined as follows. The first coil conductor 17 and the second coil conductor 18 each have a portion that extends in a substantially arcuate shape. Referring now to FIG. 4, the first coil conductor 17 of the first coil 11 is described below. As illustrated in FIG. 4, a tangent T is drawn sequentially along the outer periphery of the coil conductor 17 from the beginning end of the coil conductor 17 to the terminating end, and when the tangent T has rotated 360 degrees, this is defined as one turn. For the coil conductor 17 illustrated in FIG. 4, the tangent T has rotated approximately 307 degrees, and hence the number of turns of the coil conductor 17 can be defined as approximately 0.85. The number of turns is defined in the same manner also for the second coil conductor 18 of the second coil 12.

The smaller the number of turns of the first coil conductor 17 and the number of turns of the second coil conductor 18, the more the stray capacitance generated between the first coil 11 and the second coil 12 can be reduced. Hence, a smaller number of turns allows for improved high-frequency characteristics of the common-mode choke coil 1.

In connection with the relatively small number of turns of each coil conductor, a first characteristic feature of the common-mode choke coil 1 resides in that the sum of path lengths L1 and L2 is less than or equal to about 3.4 mm, the path length L1 being the path length of the first coil 11, the path length L2 being the path length of the second coil 12. Due to this characteristic feature, the stray capacitance generated between the first coil 11 and the second coil 12 can be reduced. This helps to ensure that, at high frequencies, the common-mode choke coil 1 can transmit differential-mode signals and suppress common-mode noise components, which allows for improved high-frequency characteristics of the common-mode choke coil 1.

In FIG. 2, the path length L1 of the first coil 11 is the total length of the path that extends from the first end 11a of the first coil 11 to the second end 11b via the following parts: the first connection end portion 23, the first coupling part 29, and the first via-conductor 27, which are included in the first extended conductor 19; and the second connection end portion 24, which is included in the second extended conductor 20. For the first coil conductor 17, the path length is measured along a substantially central portion in the width direction.

Likewise, in FIG. 2, the path length L2 of the second coil 12 is the total length of the path that extends from the third end 12a of the second coil 12 to the fourth end 12b via the following parts: the third connection end portion 25, the second coupling part 30, and the second via-conductor 28, which are included in the third extended conductor 21; and the fourth connection end portion 26, which is included in the fourth extended conductor 22. For the second coil conductor 18, the path length is measured along a substantially central portion in the width direction.

In actuality, the above-mentioned path length measurement is performed as described below. First, the multilayer body 2 is ground in the stacking direction to expose the third connection end portion 25 and the second coupling part 30. The path length of the third connection end portion 25, and the path length of the second coupling part 30 are then

measured with a measuring microscope. The grinding is further allowed to proceed to expose the second coil conductor **18** and the fourth connection end portion **26**, and the path length of the second coil conductor **18** and the path length of the fourth connection end portion **26** are then measured with the measuring microscope. The grinding is further allowed to proceed to expose the first coil conductor **17** and the second connection end portion **24**, and the path length of the first coil conductor **17** and the path length of the second connection end portion **24** are then measured with the measuring microscope. The grinding is further allowed to proceed to expose the first connection end portion **23** and the first coupling part **29**, and the path length of the first connection end portion **23** and the path length of the first coupling part **29** are then measured with the measuring microscope.

Meanwhile, another multilayer body **2** is prepared. The multilayer body **2** is ground in a direction orthogonal to the stacking direction of the multilayer body **2** to expose the first via-conductor **27** and the second via-conductor **28**. The respective lengths of the first and second via-conductors **27** and **28** in the stacking direction are then measured with the measuring microscope.

Subsequently, the sum of the lengths measured as mentioned above, that is, the length of the third connection end portion **25**, the length of the second coupling part **30**, the length of the second via-conductor **28**, the length of the second coil conductor **18**, and the length of the fourth connection end portion **26**, is found and taken as the path length of the second coil **12**. Likewise, the sum of the length of the first connection end portion **23**, the length of the first coupling part **29**, the length of the first via-conductor **27**, the length of the first coil conductor **17**, and the length of the second connection end portion **24** is found and taken as the path length of the first coil **11**.

Preferably, as clearly illustrated in FIG. 3, with the first coil conductor **17** and the second coil conductor **18** being viewed in plan in the stacking direction of the multilayer body **2**, the first coil conductor **17** and the second coil conductor **18** have no portion where the two coil conductors overlap each other, except for a portion where the two coil conductors cross each other. This also contributes to reducing the stray capacitance generated between the first coil **11** and the second coil **12**. As a result, the high-frequency characteristics of the common-mode choke coil **1** can be improved.

As is apparent from FIG. 3, with the first coil conductor **17** and the second coil conductor **18** being viewed in plan in the stacking direction of the multilayer body **2**, the first coil conductor **17** and the second coil conductor **18** cross each other at two locations. By ensuring that the first coil conductor **17** and the second coil conductor **18** cross each other at two or less locations in this way, the stray capacitance generated between the first coil conductor **17** and the second coil conductor **18** is reduced. This can contribute to improved high-frequency characteristics.

Preferably, the first coil conductor **17** and the second coil conductor **18** have a distance between each other of greater than or equal to about 6 μm and less than or equal to about 26 μm (i.e., from about 6 μm to about 26 μm). If the distance is less than about 6 μm , this may cause the stray capacitance generated between the first coil conductor **17** and the second coil conductor **18** to become large enough to degrade high-frequency characteristics. By contrast, if the distance is greater than about 26 μm , this may cause a decrease in the coefficient of coupling between the first coil **11** and the second coil **12**.

Although each of the non-conductor layers **3a**, **3b**, **3c**, **3d**, and **3e** is depicted in FIG. 2 as being a single layer, at least some of these non-conductor layers may be made up of plural layers. Accordingly, for example, the above-mentioned adjustment of the distance between the first coil conductor **17** and the second coil conductor **18** may be made either by changing the thickness of the non-conductor layer **3c** formed as a single layer, or by changing the number of layers constituting the non-conductor layer **3c**.

Preferably, each of the first coil conductor **17** and the second coil conductor **18** has a line width of greater than or equal to about 10 μm and less than or equal to about 24 μm (i.e., from about 10 μm to about 24 μm). If the line width is less than about 10 μm , this may cause the coil conductors **17** and **18** to have an increased direct-current resistance. By contrast, if the line width is greater than about 24 μm , this may cause the stray capacitance generated between the first coil conductor **17** and the second coil conductor **18** to become large enough to degrade high-frequency characteristics.

A second characteristic feature of the common-mode choke coil **1** resides in that the first lower-face electrode portion **13b** of the first terminal electrode **13**, the second lower-face electrode portion **14b** of the second terminal electrode **14**, the third lower-face electrode portion **15b** of the third terminal electrode **15**, and the fourth lower-face electrode portion **16b** of the fourth terminal electrode **16** each have an area of less than or equal to about 0.034 μm^2 , and that, preferably, the first upper-face electrode portion **13c**, the second upper-face electrode portion **14c**, the third upper-face electrode portion **15c**, and the fourth upper-face electrode portion **16c** each likewise have an area of less than or equal to about 0.034 μm^2 .

The above-mentioned characteristic feature helps to reduce the stray capacitance between each of the terminal electrodes **13** to **16** and the first coil **11**, and the stray capacitance between each of the terminal electrodes **13** to **16** and the second coil **12**. As a result, the high-frequency characteristics of the common-mode choke coil **1** can be improved.

The first lower-face electrode portion **13b**, the second lower-face electrode portion **14b**, the third lower-face electrode portion **15b**, and the fourth lower-face electrode portion **16b**, as well as the first upper-face electrode portion **13c**, the second upper-face electrode portion **14c**, the third upper-face electrode portion **15c**, and the fourth upper-face electrode portion **16c** are depicted in FIG. 1 as having a substantially semi-circular shape. Alternatively, these electrode portions may have another shape, for example, a substantially rectangular shape.

The only minimum requirement to be met to attain the above-mentioned effect, that is, reduction of stray capacitance, is that the first lower-face electrode portion **13b**, the second lower-face electrode portion **14b**, the third lower-face electrode portion **15b**, and the fourth lower-face electrode portion **16b** each have an area of less than or equal to about 0.034 μm^2 . In this regard, the presence of a common-mode choke coil that does not include the first upper-face electrode portion **13c**, the second upper-face electrode portion **14c**, the third upper-face electrode portion **15c**, and the fourth upper-face electrode portion **16c** in the first place is also to be taken into consideration. Nevertheless, if a common-mode choke coil includes the first upper-face electrode portion **13c**, the second upper-face electrode portion **14c**, the third upper-face electrode portion **15c**, and the fourth upper-face electrode portion **16c**, by ensuring that each of the upper-face electrode portions **13c**, **14c**, **15c**, and **16c** like-

wise has an area of less than or equal to about $0.034 \mu\text{m}^2$, more reliable and more pronounced reduction of stray capacitance can be accomplished.

The lower limit of the area of each of the first lower-face electrode portion **13b**, the second lower-face electrode portion **14b**, the third lower-face electrode portion **15b**, and the fourth lower-face electrode portion **16b** is, for example, about $0.004 \mu\text{m}^2$. It is preferable, however, that the lower limit of the above-mentioned area be about $0.012 \mu\text{m}^2$ to ensure sufficient strength with which the common-mode choke coil **1** is fixed to the mounting substrate when mounted onto the mounting substrate.

The terminal electrodes **13** to **16** extend over an area from the upper face **5** to the lower face **6**. In this regard, the respective portions of the terminal electrodes **13** to **16** that are provided on the first lateral face **7** or the second lateral face **8**, namely the first lateral-face electrode portion **13a**, the second lateral-face electrode portion **14a**, the third lateral-face electrode portion **15a**, and the fourth lateral-face electrode portion **16a**, each have a width on the first lateral face **7** or the second lateral face **8** (the width of the first lateral-face electrode portion **13a** on the first lateral face **7** is denoted by "W1" in FIG. 1) of preferably greater than or equal to about 0.1 mm and less than or equal to about 0.25 mm (i.e., from about 0.1 mm to about 0.25 mm), more preferably greater than or equal to about 0.15 mm. If the above-mentioned width is less than about 0.1 mm, this may result in insufficient fixing strength when the common-mode choke coil **1** is mounted onto the mounting substrate. By contrast, if the above-mentioned width is greater than about 0.25 mm, this may lead to degradation of the high-frequency characteristics of the common-mode choke coil **1**.

The first upper-face electrode portion **13c** of the first terminal electrode **13** is depicted in FIG. 1 as having a dimension E in a direction orthogonal to the direction of width of the first upper-face electrode portion **13c**. In this regard, the respective lower-face electrode portions of the terminal electrodes **13** to **16**, namely the first lower-face electrode portion **13b**, the second lower-face electrode portion **14b**, the third lower-face electrode portion **15b**, and the fourth lower-face electrode portion **16b**, as well as the respective upper-face electrode portions of the terminal electrodes **13** to **16**, namely the first upper-face electrode portion **13c**, the second upper-face electrode portion **14c**, the third upper-face electrode portion **15c**, and the fourth upper-face electrode portion **16c**, each have a dimension E of preferably greater than or equal to about 0.02 mm and less than or equal to about 0.2 mm (i.e., from about 0.02 mm to about 0.2 mm), more preferably less than or equal to about 0.17 mm. A dimension E less than about 0.02 mm may cause a decrease in the strength with which the common-mode choke coil **1** is fixed to the mounting substrate when mounted onto the mounting substrate. By contrast, a dimension E greater than about 0.2 mm may lead to degradation of the high-frequency characteristics of the common-mode choke coil **1**.

Reference is now made to a preferred manufacturing method for the common-mode choke coil **1**.

The following process is conducted to produce a glass-ceramic sheet that is to become each non-conductor layer **3**. First, K_2O , B_2O_3 , and SiO_2 , and as required, Al_2O_3 are weighed in predetermined ratios, put into a crucible made of platinum, and melted by being raised to a temperature of about 1500 to 1600° C. in a firing furnace. The resulting melted substance is rapidly cooled to yield a glass material.

An example of the above-mentioned glass material is a glass material containing at least K, B, and Si, with K

contained at a K_2O equivalent of about 0.5 to 5 mass %, B at a B_2O_3 equivalent of about 10 to 25 mass %, Si at an SiO_2 equivalent of about 70 to 85 mass %, and Al at an Al_2O_3 equivalent of about 0 to 5 mass %.

Subsequently, the above-mentioned glass material is pulverized to obtain glass powder with a D50 particle size (particle size equivalent to 50% of the volume-based cumulative percentage) of about 1 to 3 μm .

Subsequently, alumina powder and quartz (SiO_2) powder both having a D50 particle size of about 0.5 to 2.0 μm are added to the above-mentioned glass powder. The resulting powder is put into a ball mill together with PSZ media. Further, an organic binder such as a polyvinyl butyral-based organic binder, an organic solvent such as ethanol or toluene, and a plasticizer are put into the ball mill and mixed together to thereby obtain a glass-ceramic slurry.

Then, the slurry is formed into a sheet with a film thickness of about 20 to 30 μm by a method such as the doctor blade method, and the obtained sheet is punched in a substantially rectangular shape. Plural glass-ceramic sheets are thus obtained.

Examples of inorganic components contained in each glass-ceramic sheet mentioned above include a dielectric glass material containing about 60 to 66 mass % of a glass material, about 34 to 37 mass % of quartz, and about 0.5 to 4 mass % of alumina.

Meanwhile, a conductive paste containing Ag as a conductive component and used for forming the first coil **11** and the second coil **12** is prepared.

Subsequently, a predetermined glass-ceramic sheet is subjected to, for example, irradiation with laser light to thereby provide the glass-ceramic sheet with a through-hole in which to place each of via-conductors **27** and **28**. Then, the conductive paste is applied to the predetermined glass-ceramic sheet by, for example, screen printing. Thus, the via-conductors **27** and **28** with the conductive paste filling the above-mentioned through-hole are formed, and the coil conductors **17** and **18**, the connection end portions **23** to **26** respectively constituting the extended conductors **19** to **22**, and the coupling parts **29** and **30** are formed in a patterned state.

Subsequently, plural glass-ceramic sheets are stacked such that the non-conductor layers **3a** to **3e** stacked in the order illustrated in FIG. 2 can be obtained. At this time, on the top and bottom of the stack of these glass-ceramic sheets, a suitable number of glass-ceramic sheets with no through-hole provided therein and no conductive paste applied thereto are further stacked as required.

Subsequently, the stacked glass-ceramic sheets are subjected to a warm isotropic press process at a temperature of about 60 to 90° C. and a pressure of about 80 to 120 MPa to thereby obtain a multilayer block.

Subsequently, the multilayer block is cut with a dicer or other device into individual discrete multilayer structures each dimensioned such that the multilayer structure can become the multilayer body **2** of each individual common-mode choke coil **1**.

Subsequently, each discrete multilayer structure thus obtained is fired in a firing furnace at a temperature of about 860 to 900° C. for about 1 to 2 hours, for example, at a temperature of about 880° C. for about 1.5 hours to thereby obtain the multilayer body **2**.

The multilayer body **2** that has undergone firing, or each discrete multilayer structure that has not undergone firing yet is preferably placed into a rotating barrel together with media, and rotated to thereby round or chamfer its edge and corner portions.

Subsequently, a conductive paste containing Ag and glass is applied to portions of the multilayer body 2 to which the connection end portions 23 to 26 are extended. At this time, an adjustment is made such that portions of the multilayer body 2 that are to become the lower-face electrode portions 13b, 14b, 15b, and 16b as well as the upper-face electrode portions 13c, 14c, 15c, and 16c each have an area of less than or equal to about $0.034 \mu\text{m}^2$. Then, the conductive paste is baked at a temperature of, for example, about 800 to 820° C. to thereby form an underlying film for each of the terminal electrodes 13 to 16. The underlying film has a thickness of, for example, about 5 μm . Then, for example, a Ni film and a Sn film are formed sequentially on the underlying film by electroplating. The Ni film and the Sn film each have a thickness of, for example, about 3 μm .

In this way, the common-mode choke coil 1 illustrated in FIG. 1 is completed.

As described above, the common-mode choke coil 1 has the first and second characteristic features. According to the first characteristic feature, the first coil 11 has the path length L1, the second coil 12 has the path length L2, and the sum of the path lengths L1 and L2 is less than or equal to about 3.4 mm. According to the second characteristic feature, at least the first lower-face electrode portion 13b, the second lower-face electrode portion 14b, the third lower-face electrode portion 15b, and the fourth lower-face electrode portion 16b each have an area of less than or equal to about $0.034 \mu\text{m}^2$. These characteristic features help to ensure that at higher frequencies, the common-mode choke coil 1 can transmit differential-mode signals and suppress common-mode noise components. An experiment conducted to verify this is now described below.

Exemplary Experiment

As illustrated in Table 1, common-mode choke coils corresponding to Sample (indicated as "S" in Table 1) 1 to Sample 19 are prepared by varying the following values: "1st coil/SG1", "2nd coil/SG2", "1st coil path length/L1", "2nd coil path length/L2", and "area of each electrode on lower/upper face". The multilayer body of the common-mode choke coil corresponding to each sample is dimensioned to have a length dimension L of 0.65 mm, a width dimension W of 0.50 mm, and a height dimension H of 0.30

mm. Each of the first and second coil conductors of the common-mode choke coil corresponding to each sample has a line width of 0.018 mm.

Referring now to FIG. 2, in Table 1, "1st coil/SG1" represents the distance from the first coil conductor 17 of the first coil 11 to each of the lateral face 7, the lateral face 8, and the end face 10 of the multilayer body 2, and "2nd coil/SG2" represents the distance from the second coil conductor 18 of the second coil 12 to each of the lateral face 7, the lateral face 8, the end face 9, and the end face 10 of the multilayer body 2. For Samples 1, 3 to 17, and 19 excluding Samples 2 and 18 in Table 1, the distances SG1 and SG2 are different from each other. Among Samples 1, 3 to 17, and 19 mentioned above, the absolute value of the difference between the distances SG1 and SG2 is smallest for Samples 1, 3, 17, and 19. In this regard, even for Samples 1, 3, 17, and 19 mentioned above, the absolute value of the difference between the distances SG1 and SG2 is 0.020 mm. Meanwhile, as described above, each of the first coil conductor 17 and the second coil conductor 18 has a line width of 0.018 mm. This means that with respect to Samples 1, 3 to 17, and 19 for which the distances SG1 and SG2 differ from each other, as illustrated in FIG. 3, there is no overlapping portion between the first coil conductor 17 and the second coil conductor 18 except for a portion where the two coil conductors cross each other.

In Table 1, "area of each electrode on lower/upper face" represents the area of each of the following respective electrode portions of the terminal electrodes 13 to 16 illustrated in FIG. 1: the first lower-face electrode portion 13b, the second lower-face electrode portion 14b, the third lower-face electrode portion 15b, the fourth lower-face electrode portion 16b, the first upper-face electrode portion 13c, the second upper-face electrode portion 14c, the third upper-face electrode portion 15c, and the fourth upper-face electrode portion 16c. For each sample, the first lower-face electrode portion 13b, the second lower-face electrode portion 14b, the third lower-face electrode portion 15b, the fourth lower-face electrode portion 16b, the first upper-face electrode portion 13c, the second upper-face electrode portion 14c, the third upper-face electrode portion 15c, and the fourth upper-face electrode portion 16c are made equal to each other in area.

TABLE 1

S No.	Sum of								Scc21 transmission characteristic

For each of the common-mode choke coils corresponding to Samples 1 to 19, the transmission characteristic for common-mode components (Scc21 transmission characteristic) and the transmission characteristic for differential-mode components (Sdd21 transmission characteristic) are obtained.

FIG. 5 and FIG. 6 respectively illustrate the Scc21 transmission characteristic and the Sdd21 transmission characteristic obtained for the common-mode choke coil corresponding to Sample 8 chosen as a representative example.

From the characteristic charts in FIGS. 5 and 6, for Sample 8, the peak position and the transmission coefficient (indicated as "TC" in Table 1) (minimum value) at the peak position are obtained with respect to the Scc21 transmission characteristic, and the respective transmission coefficients at 20 GHz, 30 GHz, and 40 GHz are obtained with respect to the Sdd21 transmission characteristic. Likewise, for each of Samples 1 to 7 and Samples 9 to 19 as well, the peak position and the transmission coefficient (minimum value) at the peak position are obtained with respect to the Scc21 transmission characteristic, and the respective transmission coefficients at 20 GHz, 30 GHz, and 40 GHz are obtained with respect to the Sdd21 transmission characteristic. The results are illustrated in Table 1.

Table 1 also illustrates "sum of coil path lengths L1+L2", which is calculated based on the "1st coil path length/L1" and the "2nd coil path length/L2".

Referring to Table 1, for each of Samples 4 to 19 with the "sum of coil path lengths L1+L2" of less than or equal to 3.4 mm, the frequency (peak position) at which the transmission characteristic Scc21 has a minimum value can be made greater than or equal to 24.6 GHz. By contrast, for each of Samples 1 to 3 with the "sum of coil path lengths L1+L2" of greater than 3.4 mm, the peak position of the Scc21 transmission characteristic is located below 24.6 GHz, and is less than or equal to 24.5 GHz.

Among Samples 4 to 19 with the "sum of coil path lengths L1+L2" of less than or equal to 3.4 mm, for Sample 13 that does not satisfy the condition that the "area of each electrode on lower/upper face" be less than or equal to $0.034 \mu\text{m}^2$, the peak position of the Scc21 transmission characteristic is 24.6 GHz.

By contrast, for each of Samples 4 to 12 and Samples 14 to 19 with the "sum of coil path lengths L1+L2" of less than or equal to 3.4 mm and the "area of each electrode on lower/upper face" of less than or equal to $0.034 \mu\text{m}^2$, the peak position of the Scc21 transmission characteristic can be made greater than or equal to 25 GHz, for example, greater than or equal to 27.9 GHz. Further, the transmission coefficient at the peak position of the Scc21 transmission characteristic can be made less than or equal to -24 dB, for example, less than or equal to -24.7 dB.

Attention is now directed to the Sdd21 transmission characteristic. As described above, Samples 4 to 12 and

15 Samples 14 to 19 satisfy the condition that the "sum of coil path lengths L1+L2" be less than or equal to 3.4 mm, and that the "area of each electrode on lower/upper face" be less than or equal to $0.034 \mu\text{m}^2$. It can be appreciated that for each of these samples excluding Sample 18, the transmission coefficient at 20 GHz can be made greater than or equal to 0.71 dB, the transmission coefficient at 30 GHz can be made greater than or equal to -1.81 dB, and the transmission coefficient at 40 GHz can be made greater than or equal to -3.09 dB, indicating that these samples allow differential-mode signals to be effectively transmitted without much attenuation.

20 As for Sample 18, the "1st coil/SG1" and the "2nd coil/SG2" are both 0.105 mm. It is thus presumed that the first coil conductor 17 and the second coil conductor 18 overlap each other at many locations, resulting in increased stray capacitance between the first coil 11 and the second coil 12, which explains the relatively large attenuation for Sample 18 such that the transmission coefficient at 20 GHz of the Sdd21 transmission characteristic is -1.23 dB, the transmission coefficient at 30 GHz of the Sdd21 transmission characteristic is -2.80 dB, and the transmission coefficient at 40 GHz of the Sdd21 transmission characteristic is -4.11 dB.

25 Although the present disclosure has been described above with reference to the illustrated embodiment, various other modifications are possible within the scope of the present disclosure.

30 For example, in one alternative embodiment, a single coil conductor included in at least one of the first and second coils may be divided in two into a first portion and a second portion, the first portion and the second portion may be disposed respectively along a first interface and a second interface, which are different interfaces between non-conductor layers, and the first portion and the second portion may be connected by a via-conductor. In this case, the path length of the single coil conductor, which constitutes a portion of the coil path length, may be regarded as the path length with the first portion of the coil conductor, the via-conductor, and the second portion of the coil conductor combined.

35 While preferred embodiments of the disclosure have been described above, it is to be understood that variations and modifications will be apparent to those skilled in the art without departing from the scope and spirit of the disclosure. The scope of the disclosure, therefore, is to be determined solely by the following claims.

40 What is claimed is:

1. A common-mode choke coil comprising:
a multilayer body including a plurality of non-conductor layers, the plurality of non-conductor layers being stacked and each made of a non-conductor, and the plurality of non-conductor layers including a first plurality of non-conductor layers and a second plurality of non-conductor layers;

15

a first coil and a second coil that are incorporated in the multilayer body, the first coil having a path length L1 and including a first coil conductor disposed along a first interface which is an interface between the first plurality of non-conductor layers, the second coil having a path length L2 and including a second coil conductor disposed along a second interface which is an interface between the second plurality of non-conductor layers and different from the first interface along which the first coil conductor is disposed, and a sum of the path length L1 and the path length L2 being from 2.91 mm to 3.74 mm;

10 a first terminal electrode and a second terminal electrode that are provided on an outer surface of the multilayer body, the first terminal electrode being electrically connected to a first end, the second terminal electrode being electrically connected to a second end, the first end and the second end being different ends of the first coil; and

15 a third terminal electrode and a fourth terminal electrode that are provided on an outer surface of the multilayer body, the third terminal electrode being electrically connected to a third end, the fourth terminal electrode being electrically connected to a fourth end, the third end and the fourth end being different ends of the second coil,

20 wherein

the multilayer body is a cuboid in shape, the cuboid having

25 an upper face and a lower face that extend in a direction in which the plurality of non-conductor layers extend, the upper face and the lower face being opposite to each other, and the lower face being a mounting face that is directed toward a mounting substrate,

30 a first lateral face and a second lateral face that couple the upper face and the lower face to each other, the first lateral face and the second lateral face being opposite to each other, and

35 a first end face and a second end face that couple the upper face and the lower face to each other and couple the first lateral face and the second lateral face to each other, the first end face and the second end face being opposite to each other,

40 the first terminal electrode has a first lateral-face electrode portion provided on the first lateral face, and a first lower-face electrode portion contiguous to the first lateral-face electrode portion and provided on a portion of the lower face,

45 the second terminal electrode has a second lateral-face electrode portion provided on the second lateral face, and a second lower-face electrode portion contiguous to the second lateral-face electrode portion and provided on a portion of the lower face,

50 the third terminal electrode has a third lateral-face electrode portion provided on the first lateral face, and a third lower-face electrode portion contiguous to the third lateral-face electrode portion and provided on a portion of the lower face,

55 the fourth terminal electrode has a fourth lateral-face electrode portion provided on the second lateral face, and a fourth lower-face electrode portion contiguous to the fourth lateral-face electrode portion and provided on a portion of the lower face, and

60 the first lower-face electrode portion, the second lower-face electrode portion, the third lower-face electrode

16

portion, and the fourth lower-face electrode portion each have an area of from $0.004 \mu\text{m}^2$ to $0.044 \mu\text{m}^2$.

2. The common-mode choke coil according to claim 1, wherein

5 the first terminal electrode further has a first upper-face electrode portion, the first upper-face electrode portion being contiguous to the first lateral-face electrode portion and provided on a portion of the upper face, the second terminal electrode further has a second upper-face electrode portion, the second upper-face electrode portion being contiguous to the second lateral-face electrode portion and provided on a portion of the upper face,

10 the third terminal electrode further has a third upper-face electrode portion, the third upper-face electrode portion being contiguous to the third lateral-face electrode portion and provided on a portion of the upper face, the fourth terminal electrode further has a fourth upper-face electrode portion, the fourth upper-face electrode portion being contiguous to the fourth lateral-face electrode portion and provided on a portion of the upper face, and

15 the first upper-face electrode portion, the second upper-face electrode portion, the third upper-face electrode portion, and the fourth upper-face electrode portion each have an area of less than or equal to $0.034 \mu\text{m}^2$.

20 3. The common-mode choke coil according to claim 1, wherein

25 at least one of the first coil conductor and the second coil conductor has a number of turns of less than or equal to 1.

30 4. The common-mode choke coil according to claim 1, wherein

35 the first coil has a first extended conductor and a second extended conductor, the first extended conductor providing the first coil with the first end, the second extended conductor providing the first coil with the second end,

40 the plurality of non-conductor layers include a third plurality of non-conductor layers, and

45 the first extended conductor includes a first connection end portion, the first connection end portion being disposed along a third interface, the third interface being an interface between the third plurality of non-conductor layers and different from the first interface along which the first coil conductor is disposed, the first connection end portion being connected to the first terminal electrode at a location on an outer surface of the multilayer body.

50 5. The common-mode choke coil according to claim 4, wherein

55 the first extended conductor includes

60 a first via-conductor, the first via-conductor being connected to the first coil conductor, the first via-conductor penetrating one non-conductor layer of the plurality of non-conductor layers in a thickness direction of the one non-conductor layer, the one non-conductor layer being located between the first coil conductor and the first connection end portion, and

65 a first coupling part, the first coupling part having a linear shape, the first coupling part being disposed along the third interface along which the first connection end portion is disposed, the first coupling part connecting the first via-conductor and the first connection end portion to each other.

17

6. The common-mode choke coil according to claim 1, wherein

when an Scc21 transmission characteristic representing a transmission characteristic for a common-mode component is measured at a frequency of from 10 GHz to 60 GHz, a peak position at which the Scc21 transmission characteristic has a minimum value is located at a frequency of greater than or equal to 25 GHz.

7. The common-mode choke coil according to claim 6, wherein

the common-mode choke coil has a transmission coefficient of less than or equal to -24 dB at the peak position at which the Scc21 transmission characteristic has the minimum value.

8. The common-mode choke coil according to claim 2, wherein

at least one of the first coil conductor and the second coil conductor has a number of turns of less than or equal to 1.

9. The common-mode choke coil according to claim 2, wherein

the first coil has a first extended conductor and a second extended conductor, the first extended conductor providing the first coil with the first end, the second extended conductor providing the first coil with the second end,

the plurality of non-conductor layers include a third plurality of non-conductor layers, and

the first extended conductor includes a first connection end portion, the first connection end portion being disposed along a third interface, the third interface being an interface between the third plurality of non-conductor layers and different from the first interface along which the first coil conductor is disposed, the first connection end portion being connected to the first

30

terminal electrode at a location on an outer surface of the multilayer body.

10. The common-mode choke coil according to claim 3, wherein

the first coil has a first extended conductor and a second extended conductor, the first extended conductor providing the first coil with the first end, the second extended conductor providing the first coil with the second end,

the plurality of non-conductor layers include a third plurality of non-conductor layers, and

the first extended conductor includes a first connection end portion, the first connection end portion being disposed along a third interface, the third interface being an interface between the third plurality of non-conductor layers and different from the first interface along which the first coil conductor is disposed, the first connection end portion being connected to the first terminal electrode at a location on an outer surface of the multilayer body.

40

11. The common-mode choke coil according to claim 8, wherein

the first coil has a first extended conductor and a second extended conductor, the first extended conductor providing the first coil with the first end, the second extended conductor providing the first coil with the second end,

the plurality of non-conductor layers include a third plurality of non-conductor layers, and

the first extended conductor includes a first connection end portion, the first connection end portion being disposed along a third interface, the third interface

55

60

65

18

being an interface between the third plurality of non-conductor layers and different from the first interface along which the first coil conductor is disposed, the first connection end portion being connected to the first terminal electrode at a location on an outer surface of the multilayer body.

12. The common-mode choke coil according to claim 9, wherein

the first extended conductor includes

a first via-conductor, the first via-conductor being connected to the first coil conductor, the first via-conductor penetrating one non-conductor layer of the plurality of non-conductor layers in a thickness direction of the one non-conductor layer, the one non-conductor layer being located between the first coil conductor and the first connection end portion, and

a first coupling part, the first coupling part having a linear shape, the first coupling part being disposed along the third interface along which the first connection end portion is disposed, the first coupling part connecting the first via-conductor and the first connection end portion to each other.

13. The common-mode choke coil according to claim 2, wherein

when an Scc21 transmission characteristic representing a transmission characteristic for a common-mode component is measured at a frequency of from 10 GHz to 60 GHz, a peak position at which the Scc21 transmission characteristic has a minimum value is located at a frequency of greater than or equal to 25 GHz.

14. The common-mode choke coil according to claim 3, wherein

when an Scc21 transmission characteristic representing a transmission characteristic for a common-mode component is measured at a frequency of from 10 GHz to 60 GHz, a peak position at which the Scc21 transmission characteristic has a minimum value is located at a frequency of greater than or equal to 25 GHz.

15. The common-mode choke coil according to claim 4, wherein

when an Scc21 transmission characteristic representing a transmission characteristic for a common-mode component is measured at a frequency of from 10 GHz to 60 GHz, a peak position at which the Scc21 transmission characteristic has a minimum value is located at a frequency of greater than or equal to 25 GHz.

16. The common-mode choke coil according to claim 5, wherein

when an Scc21 transmission characteristic representing a transmission characteristic for a common-mode component is measured at a frequency of from 10 GHz to 60 GHz, a peak position at which the Scc21 transmission characteristic has a minimum value is located at a frequency of greater than or equal to 25 GHz.

17. The common-mode choke coil according to claim 8, wherein

when an Scc21 transmission characteristic representing a transmission characteristic for a common-mode component is measured at a frequency of from 10 GHz to 60 GHz, a peak position at which the Scc21 transmission characteristic has a minimum value is located at a frequency of greater than or equal to 25 GHz.

18. The common-mode choke coil according to claim 1, wherein the sum of the path length L1 and the path length L2 is less than or equal to 3.4 mm.

19. The common-mode choke coil according to claim **1**,
wherein the sum of the path length L1 and the path length
L2 is less than or equal to 3.33 mm.

20. The common-mode choke coil according to claim **1**,
wherein the area is less than or equal to 0.034 μm^2 . 5
